UNITED STATES PATENT OFFICE.

ALFRED HARB, OF NEW YORK, N. Y., ASSIGNOR TO LOUISA HARB, OF NEW YORK, N. Y.

AUTOMATIC FLYING-MACHINE.

1,275,251.

Specification of Letters Patent. Patented Aug. 13, 1918.

Application filed October 11, 1917. Serial No. 186,087.

To all whom it may concern:

Be it known that I, ALFRED HARB, a subject of the Emperor of Austria, residing at New York, in the county of New York and State of New York, have invented new and useful Improvements in Automatic Flying-Machines, of which the following is a specification.

This invention relates to motor driven heavier than air machines, and the main object of the same is the provision of a machine of this character having main planes or wings fashioned in general like the wings of a bird, and having combined with these planes, air pockets or wings, which are held closed and rigid with the said main planes when the machine is driven forward in any variety of normal positions, but which are adapted to move relatively with respect thereto, and to open out in response to air pressure, in the event the machine should fall because of accident or disability.

A further object of the invention is to provide a flying machine of this character with a wheeled pilot's seat, which, weighted with the pilot, is adapted to be moved aft to cause the machine to tilt rearwardly, bringing the air pockets or wings into position to be acted on by the air pressure and to be opened under falling movement.

A still further object of the invention is to combine the air pockets or wings with the main planes and to connect them with each other, in such manner that the connecting means therefor traverses the path of the wheeled pilot's seat, so that when said seat is moved, it will automatically cause the severance of the connecting means, freeing the air pockets for the support of the machine against rapid and perhaps disastrous falling toward the earth.

With these and other objects in view, the invention resides in the details of construction and in the combination and arrangement of parts hereinafter described and shown in the accompanying drawings, forming a material part of this specification, and in which:

Figure 1 is a top plan view of the flying machine, parts being broken away.

Fig. 2 is a view in front elevation.

Fig. 3 is a view in side elevation, parts being broken away.

Fig. 4 is a cross sectional view, taken approximately in the direction of the line 4—4 of Fig. 3.

Fig. 5 is a fragmental elevational view, partly in section, illustrating in particular the arrangement of the pilot's house and the course of travel of the pilot's wheeled seat.

Fig. 6 is a rear elevational view of the pilot's wheeled seat, taken approximately on the line 6—6 of Fig. 7.

Fig. 7 is a side elevational view of the pilot's wheeled seat and the supporting elements therefor, showing also the mechanism employed for advancing the seat on its track.

Fig. 8 is a view in perspective of the cylindrical propeller detached.

Fig. 9 is a view in perspective of a main plane with the air pockets or wings combined therewith, the latter being shown in their detached elevated position and also being shown partially opened for engagement with the air.

Fig. 10 is a view in perspective of a portion of the skeleton frame for the main planes, showing in particular how supporting elements for the air pockets or wings are pivoted thereto.

Fig. 11 is a cross sectional view, taken on the line 11—11 of Fig. 9.

Fig. 12 is a similar view, taken on the line 12—12 of Fig. 1.

Fig. 13 is a similar view, taken on the line 13—13 of Fig. 1.

Fig. 14 is a similar view, taken on the line 14—14 of Fig. 9.

With more particular reference to the accompanying drawings, the numeral 18 denotes parallel longitudinal chassis members, which are bowed upwardly intermediate their lengths, and which terminate in the rounded ends 19 and 20, of which the front end 19 is formed intermediate its length with the bearing 21, through which passes the propeller shaft 22, on the forward end of which is mounted the cylindrical propeller 23.

Connecting the longitudinal chassis members 18 at the forward end are the spaced-apart cross members 24 (Fig. 1), upon which

is mounted the platform for the support of the motor 16, the steering device, as 27, and the wheeled pilot's seat 28 (Fig. 5). The quarters for the pilot are preferably completed by providing the cylindrical top or housing 29, which is designed to be rolled or folded up in any suitable manner to allow a wide vision of the surroundings.

Rigidly secured to the chassis elements 18 10 and projecting therefrom at each side, much like the wings of a bird projects from its body when in flight, are the elongated skeleton frames 30 for the main planes of the machine. As best seen in Figs. 1, 3 and 5, 15 these frames 30 curve upwardly and rearwardly terminating in the tips or ends 31, the central portions thereof being bowed longitudinally. These planes are covered with the usual air-proofed china silk or 20 other suitably prepared fabric.

To the front arm 32 of each frame 30, are pivoted at 33 a pair of wing supporting arms 34 and 35, it being noted in this connection, as shown in Figs. 9 and 10, that 25 at the point of pivoting 33, the base arm 32 is provided with a shoulder 36, and also that the adjacent ends of the supporting arms 34 and 35 are likewise provided with shoulders as 37, which are adapted to butt 30 against the said shoulder 36 whereby to limit the outward movement of the arms 34 and 35. Mounted around the arms 34 and 35, on each side of the base arm 32, are air-proof coverings or pocket-like wings 38, 35 the rear edges of which, when the said arms 34 and 35 are in alined position with the base arm 32, extend to and coincide with the edges of the covering on the main wing 30, as best shown in Fig. 1, the rear portion 40 of the coverings 38 beyond the point of pivoting 33, being rigidly secured to the framework 30 of the main wing along with its covering.

By arranging the coverings 38 in this 45 manner, I provide for each main plane two pocket-like wings having openings as 39 and 40, at their lower ends, the outer sides of which, engaged upon the spring-like bracing ribs as 41, secured to and projecting 50 from the arms 34 and 35, as best shown in Fig. 9, flare outwardly from the main plane. Provided in the marginal edges of the coverings around the openings 39 and 40, are a plurality of spaced-apart eyelets as 42. 55 Similar eyelets are also provided in the adjacent marginal edge of the covering on the main plane 30. By passing a rope as 43, or other suitable lacing means through the eyelets 42 in an obvious manner, I interlace or secure the pocket wings fast to and 60 coincident with the main plane 30, so that taken together all form one wing or plane, there being, of course, on the opposite side of the chassis, another composite wing or

plane constructed in an identical manner. 65 The ropes as 43, which are used to secure the wings on each side of the chassis, are then drawn across the chassis elements 18 (Fig. 1) at the rear of the pilot's seat 28, and there united and held rigidly and tautly 70 in elevated position for convenient severance, in the manner to be later described.

The seat 29 for the pilot, as best shown in Figs. 5, 6 and 7, is fastened rigidly upon a supporting frame 44, which is provided with 75 two pairs of legs 45 and 46. To the lower ends of each pair of legs is secured the axles 47 and 48, upon the opposite ends of each of which are rotatably mounted the wheels 49, which are rotatably engaged 80 against displacement in the channels 50, provided in the confronting sides of the track rails 51, mounted longitudinally of the chassis upon the cross pieces 24.

Projecting outwardly from the front legs 85 45, at each side and rigid therewith, above the rails 51, are the studs 52 upon the outer ends of which are pivoted the dogs 53 adapted to engage the teeth 54 provided in the adjacent outer faces of the rails 51. Links 90 55 pivotally connect the opposite ends of the dogs 53 with the short arms of the bell crank operating levers 56, pivoted at 57 to the exterior sides of the seat as shown. Combined with the operating levers 56 are 95 the usual locking levers 58, operable in the notched racks 59 secured to the exterior sides of the seat. Under this construction, the wheeled seat 28, upon the release of the dogs 53 by the proper operation of the levers 100 56, will travel rearwardly by gravity, when the machine is tilted rearwardly, the movement in this direction being limited by the stop 60 against which the buffer device 61, attached to the rear of the seat 28 is arranged to butt. The object of this arrangement is to enable the pilot, in the event of the stopping of the motor or of an accident befalling the machine, to transfer his weight 105 in addition to the weight of the wheeled seat 110 to the rear portion of the machine, thereby causing the same to tilt rearwardly bringing the pocket wings 38 into position to be opened by the air pressure. In order automatically to loosen the pocket wings as the 115 pilot's seat is moved rearwardly, I provide the seat on each side of the buffer element 61 with knives as 62 formed with V-shaped cutting edges, which knives are so located 120 that they will engage and sever the united ropes 43, when the seat is moved rearwardly.

The ropes 43 thus being severed, releasing the connections at the rear ends between the pocket wings and the main planes, these pocket wings are free to open or spread transversely, and at the same time to extend longitudinally outwardly owing to the hinge 33. In this manner I combine with the main

planes 30 the pocket wings 38, so that the latter will be opened and extended in response to the air pressure, thereby providing air pockets adapted effectively to increase 5 resistance to the falling movement of the machine, it being noted also in this connection that if the motor is still operating, the peculiar cylindrical form of the propeller blades 23 will also serve as an additional 10 force to prevent the rapid falling of the machine.

In the embodiment of the invention herein shown, I prefer to provide outwardly projecting horizontal planes as 63 along the 15 chassis elements 18. These planes 63 increase in width toward the rear of the machine, ending in a straight edge 64. In addition to serving as supporting and stabilizing planes in the usual way, these planes 20 have another function in that when the machine is falling, they tend to deflect the movement of the air into the pocket wings, thereby increasing resistance to the falling movement of the machine, and at the same 25 time these planes, in cutting through the air, have a tendency to cause the falling machine to descend by zig-zag steps instead of in a perpendicular course.

In the present embodiment of my invention, 30 the rudder devices include the horizontal plane 65, which is hinged at 66 to the supports as 67 rigidly projecting from the rounded rear end 20 of the chassis. This rudder is operated by wires as 68 which are 35 secured to it as at 69, and which extend by the usual system of pulleys within reach of the pilot from his seat 29. Hinged at 70 upon the support 67 is a vertical rudder 71, the movement of which steers the machine 40 to the right or left. To this rudder is attached at 72 the wires 73, which also extend by the usual system of pulleys to the operating levers near the pilot's seat.

Having thus described my invention, what 45 I claim is:—

1. In a flying machine, the combination of a rectangular frame, fixed wing-like planes projecting therefrom at each side near the forward end, sustaining and stabilizing planes located aft of said fixed wing-like planes, a housing located upon the frame between said fixed wing-like planes, driving and steering mechanism located in said housing, a trackway beginning adjacent 50 said steering mechanism and extending aft upon the frame, a pilot's chair operatively secured upon the trackway and adapted to travel aft thereupon whereby under the weight of the chair and its occupant to tilt 55 the machine rearwardly, pocket wings adjustably combined with the wing-like planes, means for partially disconnecting the pocket wings from the wing-like planes so that the former may be extended and opened in 60 response to air pressure when the machine 65 is tilted rearwardly by the travel of said pilot's chair.
2. In a flying machine, the combination of a rectangular frame, fixed wing-like planes projecting therefrom at each side 70 near the forward end, sustaining and stabilizing planes projecting from the frame longitudinally thereof, a steering device mounted upon the frame between the wing-like planes, a track extending aft upon the 75 frame from the steering device, a wheeled pilot's chair operatively mounted upon the track and normally locked therewith adjacent the steering device, means combined with the chair and controlled by the pilot 80 to permit the chair to travel aft upon the track, pocket wings combined with the wing-like planes and movable relatively with respect thereto, means for detachably connecting the pocket wings in closed position with 85 the wing-like planes along their rear marginal edges, and means controlled by the movement aft of the chair upon its track to inaugurate the detachment of said connecting means, permitting the pocket wings to 90 open in response to air pressure under falling movement.
3. In a flying machine, a rectangular frame structure bowed longitudinally, main wings tapered and bowed longitudinally 95 projecting rigidly therefrom, pocket-wings co-extensive with the main wings operatively connected thereto to co-operate with the same in flying, said pocket wings opening toward the rear of the machine and 100 being capable, when partly disconnected, of movement relatively with respect to the main wings and being adapted to open in planes traversing those of said main wings, a trackway arranged upon the frame longitudinally thereof, a wheeled pilot's chair 105 engaged with said trackway, said chair being normally locked upon said trackway between the main wings, means operable by the occupant of the chair to permit the same 110 to travel aft upon the trackway whereby to tilt the machine rearwardly, means automatically operable by the rearward movement of said chair to partly disconnect the pocket-wings from the main wings permitting 115 the open ends of the air pockets in response to the air pressure of the same under falling movement to open and resist the falling movement of the machine and longitudinal planes carried by the frame 120 aft of the main planes whereby to deflect the stratum of air toward the air pockets.
4. The combination with a flying machine including a bowed rectangular frame and elongated bowed wing-like planes projecting therefrom forward of its longitudinal center, of pocket wings co-extensive with 125 said planes and combined therewith for co-

operation in flying, said pocket wings being capable when partly detached of relative movement with respect to the planes and being adapted to open out in response to air pressure on the same under falling movement, and a chair carriage under the control of the pilot movable longitudinally of the frame and aft of said planes whereby to tilt the machine rearwardly bringing the said planes into vertical or oblique position 10 with the openings of the pocket wings facing downwardly.

In testimony whereof I have signed my name to this specification.

ALFRED HARB.
